UNITED STATES PATENT OFFICE.

JOHN H. EICKERSHOFF, OF CINCINNATI, OHIO.

GAME-BOARD.

SPECIFICATION forming part of Letters Patent No. 636,508, dated November 7, 1899.

Application filed April 21, 1899. Serial No. 713,918. (No model.)

To all whom it may concern:

Be it known that I, JOHN H. EICKERSHOFF, a citizen of the United States, residing at Cincinnati, in the county of Hamilton and State 5 of Ohio, have invented certain new and useful Improvements in Game-Boards, of which the following is a specification.

The object of my invention is to produce a mechanical game-board by means of which a 10 great variety of games may be played with the same apparatus, by which many of the old and well-known indoor games may be played by different means and with variations of method which render them more attractive, by which 15 novel and amusing combinations of questions and answers, quotations, or the like may be produced, and by which the variety of such combinations may be multiplied at will; and my invention consists in the mechanism and 20 combinations and arrangements of parts hereinafter described and claimed.

In the drawings, Figure 1 is a plan view of a game-board embodying my invention; Fig. 2, a section on line 2 2 of Fig. 1; Fig. 3, a plan 25 view of a modification embodying my invention; Fig. 4, a section on line 4 4 of Fig. 3. Figs. 5 and 6 show in plan disks selected to illustrate the method of arrangement for some of the games.

30 The reference-letter A denotes a box or case adapted to contain my device, and B a plate mounted to rotate in the box A.

C, C', C², and C³ represent game-disks mounted to rotate on the plate B, D a flat 35 spring adapted to contact with the peripheries of the disks, and E an indicator.

The containing-box A and plate B may be of any desired form and are preferably made of light wood or heavy cardboard, the plate being mounted to rotate freely in the box. This 40 rotatable mounting may be accomplished in various ways, two of which are illustrated in the drawings. In Figs. 1 and 2 the plate is shown as carried by a central knob b, which is pivoted to the bottom of the box by means 45 of pivot-screw b'. At the base of the pivot the bottom is preferably reinforced by a plate a, which also serves as the bearing for the knob b. In Figs. 3 and 4 the knob b is hung 50 upon the pivot b² and swings clear of the reinforcing-plate a, thus avoiding friction. At

intervals on the plate B are pivoted disks C C', &c., preferably with their peripheries projecting beyond the periphery of the plate, so that upon rotation thereof they contact with 55 the flexible spring D, which may be secured to the side of the box A, as at d. This pivoted mounting may also be accomplished in various ways, two of which I have illustrated in the drawings.

In Figs. 1 and 2 I have shown each disk as provided with a central hub c, adapted to take over pivot-pins c' on the plate B and rotate thereon, with the upper surface of the plate as a bearing. The hub c is open at 60 both ends, so that either face of the disks may be exposed.

In Figs. 3 and 4 I have shown the plate B as provided with pivoted disks c², permanently mounted thereon, each of which is provided 65 with a square or other polygonal projection c³. The disks C C', &c., are provided with corresponding polygonal-shaped central openings adapted to take over projections c³ and hold their disks in position on disks c² with either 70 face exposed. The upper faces of disks c² when not covered by disks C C', &c., may also be used. The latter method is preferable, as it is not necessary to provide each disk with 75 a separate hub, one set of disks c² serving as 80 mounting for all the disks C C', &c. The faces of the disks C C', &c., are provided with various configurations characteristic of the game to be played, and an indicator E is mounted 85 on knob b, with a hand e pointing to the periphery of each disk.

In Fig. 1 I have shown disks adapted for a game of question and answer, in which each disk is divided into a number of sectors, each containing a printed answer to some general 90 question relating, for instance, to one of the important factors in human life and the disks named in accordance with the factors selected. Thus the four disks in Fig. 1 are named, respectively, "Business," "Pleasure," "Love," 95 and "Hate" and each provided with its appropriate answers. The operator asks, silently or otherwise, a question relating to the subject-matter indicated by the name given to one of the disks and then whirls the plate B 100 by means of the knob b. As the disks C are carried around by the plate their peripheries

contact with the spring D, which imparts to them a rapid rotary movement, which continues for some time after the contact has ceased. When all movement has ceased, the hands *e* 5 point to an answer on the selected disk.

In Fig. 3 I have illustrated the application of my invention to another form of game, which, so far as I am aware, is in itself new. In this case there are five disks C C', &c., 10 each divided into ten sectors, in each of which is placed one of the numbers from "1" to "50," there being in all fifty sectors, one for each number up to fifty. In this case also I have shown the spring D' of a slightly- 15 different form from spring D of Fig. 1, but performing the same function in the same way. The object is to count from one to a selected number—fifty, for instance—by successive operations of the device, and the game 20 is adapted for any number of players. The first player, if there be more than one, turns the knob, and if when the disks stop either hand registers with the figure "1" one is counted. If at the same operation another 25 hand happens to register at the figure "2," two is also counted, and the player may add the "1" and "2," thereby counting three. If a third hand happens to register with the figure "4," four is counted, and by adding the 30 "1" five, by adding the "2" six, by adding the "3" seven, &c., the plan being to count any successive numbers when indicated by the hand or obtained by addition of the numbers indicated by all the hands, it being required, however, that at each operation one 35 hand must point to the player's starting-number for that operation. If the starting-number is not indicated, the player's turn is at an end. In Fig. 3 I have shown the hands registering with the numbers "1," "2," "4," "8," 40 and "16." This combination permits counting thirty-one by one rotation. This game affords both amusement and intellectual training, as the great number of permutations obtainable from the five indicated numbers requires no little exercise of the mathematical faculty to detect those required on the spur of the moment. This game may be varied 45 indefinitely by changes in the number of disks or number of sectors on each disk or numbers 50 to be obtained or the method of counting without affecting in any degree the mechanical principles upon which it depends.

In Figs. 5 and 6 I have illustrated still other 55 configurations of disks adapted to use in other games. Fig. 5 shows a disk adapted for use in spelling matches, which is divided into ten sectors, each labeled with a different letter, either capital or small. The "J" and "I" being 60 made identical, the fifty sectors provided by five such disks accommodate all the letters of the alphabet, both capital and small. In this game the letters indicated by the hands *e* after successive whirlings of the plate B are 65 to be used in their proper order in spelling a selected word. Fig. 6 shows a disk adapted for use in playing dominoes, thus providing

for the twenty-eight different combinations. A number of counters or markers are placed on the table, and a certain number are given 70 to each of the players, who endeavor to get rid of them in accordance with the ordinary rules of dominoes, the playing-hand of each player at each turn consisting of the four dominoes indicated by the four indicator- 75 hands after his operation of the device.

The form of my invention illustrated and described in this specification is capable of many modifications without departing from its spirit, and I do not wish to limit myself 80 to any specific form of mechanism or its application to any specific kind of game; but

What I claim as my invention is—

1. The combination, in a game-board, of a revoluble plate; one or more rotatable disks 85 mounted on the plate bearing insignia characteristic of the game to be played; an indicator adapted to designate sectors of the disks corresponding with the individual elements of the groups of insignia; means for 90 rotating the plate; and a contact-piece adapted to engage with the peripheries of the disks as the plate rotates.

2. The combination, in a game-board, of a revoluble plate; one or more rotatable disks 95 mounted on the plate bearing insignia characteristic of the game to be played; an indicator adapted to designate sectors of the disks corresponding with the individual elements of the group of insignia; a knob on the 100 plate whereby it may be revolved; and a contact-piece adapted to engage with the peripheries of the disks as the plate rotates.

3. The combination, in a game-board, of a revoluble plate; one or more rotatable disks 105 mounted on the plate bearing insignia characteristic of the game to be played; an indicator mounted on the plate and adapted to designate sectors on the disks corresponding with the individual elements of the groups of 110 insignia; a knob on the plate whereby it may be revolved; and a spring adapted to contact with the peripheries of the disks as the plate rotates.

4. The combination, in a game-board, of a 115 revoluble plate; one or more pivots arranged at intervals on the plate; one or more disks bearing insignia characteristic of the game to be played and adapted to rotate on the pivots; an indicator mounted on the plate and 120 adapted to designate characters on the disks; means for revolving the plate; and a spring adapted to contact with the peripheries of the disks as the plate rotates.

5. The combination in a toy, of a revoluble 125 plate; one or more supporting-disks pivoted at intervals on the plate and provided with central polygonal projections; one or more disks bearing insignia characteristic of the game to be played and central polygonal-shaped openings adapted to take over the 130 projections on the supporting-disks; an indicator mounted on the plate and adapted to designate characters on the disks; means for

revolving the plate; and a spring adapted to contact with the peripheries of the disks as the plate rotates.

6. The combination, in a game-board, of a plate; a series of disks pivotally mounted on said plate, each disk bearing a differing series of numbers arranged in sectors on the disk, and means for imparting an independent rotation to the disks.

10 7. The combination, in a game-board, of a plate; a series of disks pivotally mounted on

said plate, each disk bearing a differing series of numbers arranged in sectors on the disk, the numbers on the several disks, when combined, constituting an unbroken series and means for imparting an independent rotation to the disks.
